MUSICAL ANNUNCIATOR

Filed Dec. 9, 1939

UNITED STATES PATENT OFFICE

2,269,098

MUSICAL ANNUNCIATOR

Leslie W. Garnett, Hopkinsville, Ky.

Application December 9, 1939, Serial No. 308,463

6 Claims. (Cl. 177—7)

This invention relates to improvements in signaling devices and pertains particularly to a novel and improved annunciator designed primarily for use upon doors of residences or other structures for announcing visitors.

The primary object of the present invention is to provide a novel annunciator in the form of a door knocker or gong which is designed to simulate a woodpecker or similar type of bird perched upon a body representing a portion of a tree limb and mounted for movement relative to such body whereby, upon such movement, the bill of the bird will contact a sound-producing element to produce a musical note.

Another object of the invention is to provide an annunciator which comprises a musical note sounding bar and a pivotally supported bird representing a woodpecker with means connected with said bird whereby it may be oscillated in such a manner as to strike the bill of the bird against the bar and thereby produce a musical note.

A still further object of the invention is to provide in a device of the character stated a novel means for effecting the oscillation of the striker which simulates a bird, whereby with each oscillation of the bird a musical note will be sounded.

The invention will be best understood from a consideration of the following detailed description taken in connection with the accompanying drawing forming part of this specification, with the understanding, however, that the invention is not to be confined to any strict conformity with the showing of the drawing but may be changed or modified so long as such changes or modifications mark no material departure from the salient features of the invention as expressed in the appended claims.

In the drawing:

Figure 1 is a vertical sectional view through the device embodying the present invention.

Figure 2 is a section on the line 2—2 of Figure 1.

Figure 3 is a vertical sectional view through the lower portion of the modified form of the device.

Referring now more particularly to the drawing, the numeral 1 designates a portion of a structure, such as a panel of a door or the like, upon which the annunciator embodying the present invention may be mounted and the numeral 2 generally designates the body of the annunciator which is in the form of an elongated member which is exteriorly finished to simulate a

limb or trunk of a tree. This elongated body may be secured by screws 3 or in any other suitable manner to the supporting panel 1 and the body 2 is chambered, as indicated at 4, this chamber opening preferably through the back of the body and through the upper end thereof but terminating a substantial distance above the lower end of the body. It is preferred that this chamber 4 be of gradually increasing size or diameter from the lower end upwardly so as to permit of the flow of the sound waves upwardly and out of the upper end of the body in the same manner that the sound waves travel through a horn.

15 Secured to the body at the lower end of the tone carrying chamber 4 and preferably in a recess 5 formed in the rear side of the body, is the lower end of a bracket arm 6, the upper end of which is bent to provide the angularly directed head 7 which is provided with a threaded opening to receive a screw 8, and this screw extends through an aperture in one end of a tone bar 9, the bar being held in position by the head 10 of the screw 8, as illustrated. The bracket supports the tone bar in upright position within the chamber 4 and in close proximity to the forward wall of the chamber and through this forward wall adjacent the upper end of the chamber there is formed a hole 11, for the purpose hereinafter stated.

The bar 9 is formed of steel or other suitable metal such as is employed in the making of chime gongs and the hole 11 constitutes a striker hole through which the bill of the bird, hereinafter described, is made to pass to contact the gong.

In the face of the body 2 below the striker hole 11 a recess 12 is formed in which is disposed the horizontal pivot pin 13. Extending 40 into the recess 12 and supported upon the pin for rocking movement in a vertical plane is the leg 14 of the bird-simulating body 15. The bill 16 of this body is provided with a striker point or tip 17, which is preferably in the form of a raw hide or similar resilient member removably attached to the bill 16 and arranged, when the body 15 is oscillated, to pass through the striker hole 11 and contact the gong bar 9.

If a greater volume of sound is desired the 50 soft or yielding tip 17 may be replaced by a metal tip. This would give a sharper, louder sound in striking the bar 9 than would be produced by the softer raw hide tip 17. An additional means, hereinafter particularly described, is provided whereby the sound produced in the

chamber 4 by the musical bar may be more clearly carried through the supporting panel 1 into the building upon which the striker is mounted.

In the lower part of the main body 2 there is provided an upwardly extending passage 18 through which extends a link bar 19, the upper end of the bar being pivotally attached at 20 to the leg 14 of the striker body 15. Adjacent the lower end of the passage 18 a forwardly extending aperture is formed, as indicated at 21, which opens into the passage 18. Upon the face of the body 2 adjacent the aperture 21 there is secured a bracket 22 which carries a horizontal pivot 23 on which is oscillatably mounted the rocker arm 24. One end of this arm extends through the aperture 21 and is pivotally connected at the lower end to the bar 19, as indicated at 25, while the outer end of the rocker arm carries the chain-supported ring 26.

The rocker arm oscillates vertically as will be readily apparent and it will be seen that upon pulling down on the outer end of this arm the rod 19 will be shifted upwardly and since the upper end of this rod is attached to the leg 14 between the pivot 13 and the body 15, the body will be raised or swung upwardly and inwardly so that the point of the bill 16 will pass through the striker hole 11 and hit the tone bar 9.

Where the present musical striker is mounted upon a door panel of ordinary weight, the tone of the bar 9 will be transmitted through the panel to the interior of the building but where such panel may be of unusually heavy construction or where it may be desired to have the tone carried into the building with greater volume or clarity, the panel or supporting body 1 may be provided at the upper end of the striker body 2 with an opening 27 covered upon the inner side of the panel by a suitable grill 27', while upon the outer side of the panel there is secured over the open upper end of the body 2, the upwardly and inwardly curving hollow cap 28 which guides or carries the sound produced by the tone bar 9 in through the opening 27 to the interior of the building. This cap may be secured in place by the upper one of the screws 3 which holds the striker device in position.

It will be understood, of course, that the sound chamber 4 may be made in different sizes so that the volume of tone produced in striking the bar 9 may be controlled or varied and while the body 2 may be formed of any suitable material, it is preferred that it be made of metal finished upon its outer side, as previously stated, to resemble the surface of a tree limb or trunk.

Figure 3 illustrates a mechanism by which electric current may be employed for causing the striker body 15 to oscillate and while only the lower portion of the modified form of the mechanism is illustrated and described, it is to be understood that the same form of striker is coupled with the actuating rod as is shown in Figure 1 connected to the actuating rod 19. In this modified form of the invention the tree limb or trunk simulating body forming the gong housing, is indicated by the numeral 29, the body being formed to provide the chamber 30 in which the gong 31 is mounted. The lower part of the body 29 forms a separate housing 32 in which is enclosed a small electric motor 33 having upon the end of the armature shaft 34 a gear pinion 35. Supported in the housing 32 upon a suitable horizontal stub shaft 36 attached at one end to one side wall of the housing, is a

gear 37 which carries a crank pin 38. The numeral 39 designates the actuating rod which couples the gear 37 with the leg of the striker body which is in the form of the bird such as is shown in Figure 1 but only the lower end of which is illustrated in connection with the present modified form of the invention, and this rod 39 is divided into the upper and lower sections 40 and 41 which are coupled together by the threaded turnbuckle sleeve 42. By means of this turnbuckle, the effective length of the rod may be varied so as to increase or decrease the position of oscillation of the striker bird with which the actuating rod 39 is connected.

The lower part of the motor housing 32 supports a push button rod 43 for reciprocatory movement, a spring of any suitable type, such as the spring 44, being connected with this rod to normally urge the same to move outwardly.

At the inner end of the rod a switch unit is mounted, which is indicated generally by the numeral 45, and which is here shown as comprising a fixed terminal 46 and a shiftable terminal 47, the rod 43 being disposed adjacent the latter terminal so that when the rod is forced inwardly this shiftable terminal will be moved into electrical engagement with the fixed terminal 46. When this is done an electric circuit is closed through the current-conducting wires 48 so as to introduce current into the motor 33 with which the wires are joined, to cause the operation of the motor. This will result in the rapid rotation of the gear 37 and the rapid oscillation of the striker element which is connected with the actuating rod 39 and thus produce a rapidly reproduced series of notes through the striking of the tone bar or gong 31 by the bill of the striker bird.

From the foregoing it will be readily apparent that the present chime knocker constitutes a novel annunciator operated in a novel manner, such an annunciator being attractive in appearance so that it provides an attractive ornament for a door or house front.

It will be understood that in the form of the invention shown in Figure 1 where the body 15 is actuated manually, this body will move outwardly or return to retracted position when the actuating lever 24 is released, by its own weight. In the form of the invention shown in Figure 3, however, the striking bar is actuated by the electric motor and in this case may stop in any position with respect to the sounding bar 31. The latter form of the invention operates to sound the bar at a high speed, whereas in the manually operated form of the invention, the striking of the bar would be at slower or less frequent intervals.

I claim:

1. An annunciator device of the character stated, comprising a supporting body formed to provide a sound chamber and having a wall aperture, a sound producing bar supported in said chamber and extending across said aperture, a striker body having a portion forming a supporting leg pivotally secured to the first body and having an elongated striking element disposed in a position to pass through said aperture for contact with said bar upon oscillation of the striker body in one direction on the pivot for the supporting leg, a reciprocable member having an end pivotally attached to said supporting leg, and means carried by the first body and operatively connected with said reciprocable member to effect rectilinear movement of the

reciprocable member and oscillation of the striker body for the projection of the striking element through the aperture into contact with the bar.

2. An annunciator of the character described, comprising an elongated body simulating a limb or trunk of a tree and having a chamber and a wall provided with an aperture opening into the chamber, a musical note producing body supported in the chamber across said aperture, a striker body simulating a bird having a supporting leg, means pivotally connecting said leg with the first body for oscillation of the striker body in the longitudinal plane of the said first body, said bird simulating striker body having a bill disposed for extension through the wall aperture for contact with said musical note producing body, and means connected with the leg of the bird simulating body for facilitating the oscillation of the latter for the projection of the bill through the aperture into contact with the note producing body.

3. In a musical note producing annunciator including an elongated body formed to provide a sound chamber, and an element for producing a sound when struck, supported within said chamber, said body having a wall aperture leading from the outside of the body into the chamber and directed toward said element, a striker body simulating a bird pivotally supported upon the first body for oscillation in a vertical plane and having a bill arranged to pass through said aperture when the striker body is oscillated in one direction for contact with said element, a vertically reciprocable actuating rod connected at one end with the striker body and extending downwardly into the first mentioned body, and electromagnetic means carried by the first mentioned body and operatively coupled with the other end of said rod for effecting reciprocation of the rod and vertical oscillation of the striker body.

4. In a musical note producing annunciator including a body, an element for producing a sound when struck, supported by the body, a striker body simulating a bird pivotally supported for oscillation relative to said element and having a bill for striking the element when the striker body is oscillated in one direction, a reciprocable actuating rod connected at one end with the striker body and means operatively coupled with the other end of said rod for effecting reciprocation of the rod and oscillation of the striker body, said rod actuat-

ing means comprising a bar pivotally supported for oscillation on an axis parallel with the axis of oscillation of the striker body and having a pivotal connection at one end with said rod and having means at its other end facilitating its oscillation on said axis.

5. A chime annunciator of the character described, comprising an elongated body exteriorly finished to represent a tree limb or trunk, the body being hollow throughout a portion of its length to form a chamber opening through an end of the body, a chime bar supported within said chamber, the body having an aperture through the wall thereof directed toward said chime bar, a striker body simulating a bird having a supporting leg, means pivotally connecting said leg with the first body for the support of the bird at the front of the first body for oscillation in a vertical plane, said bird body having a bill arranged to pass through said opening and contact the chime bar, an actuating rod partially enclosed within the first body and pivotally attached at one end to the said leg of the bird body and extending downwardly therefrom, and means supported by the lower part of the first body and coupled with said bar for effecting a rectilinear movement of the bar and the oscillation of the striker bird body.

6. A chime annunciator of the character described, comprising an elongated body exteriorly finished to represent a tree limb or trunk, the body being hollow throughout a portion of its length to form a chamber opening through an end of the body, a chime bar supported within said chamber, the body having an aperture through the wall thereof directed toward said chime bar, a striker body simulating a bird having a supporting leg, means pivotally connecting said leg with the first body for oscillation in a vertical plane, said bird body having a bill arranged to pass through said opening and contact the chime bar, an actuating rod partially enclosed within the first body and pivotally attached at one end to the said leg of the bird body and extending downwardly therefrom, and means supported by the lower part of the first body and coupled with said bar for effecting a rectilinear movement of the bar and the oscillation of the striker bird body, said bill having the tip portion removable for substitution by a corresponding tip portion of different material.

LESLIE W. GARNETT.
